UNITED STATES PATENT OFFICE.

ARTHUR A. PAYNE, OF HUMBOLDT, KANSAS.

AMUSEMENT DEVICE.

Application filed January 24, 1927. Serial No. 163,125.

This invention relates to amusement devices wherein a novelly constructed counting head is used at the end of a semi-circular track to indicate the score made by the 5 player of the game.

The primary object of the instant invention is the contemplation of certain improvements and refinements of construction the use of which will render the counting head 10 of the device cheap to make, easier to assemble and less likely to get out of order.

Another object of the invention is the provision of a counting head for amusement devices which includes a plurality of slots 15 through which the operating arms for the counting drops may project when the drop-setting mechanism of the device is operated.

An even further object of this invention is to provide a novelly constructed ball catching trough which is constructed to include means for precluding the return of the thrown ball through the entrance to the 20 counting head.

Many minor objects will appear during 25 the course of the detailed specification referring to the accompanying drawing, in which:

Figure 1 is a side elevation of an amusement device having a counting head made in 30 accordance with this invention.

Fig. 2 is an enlarged vertical central section through the novelly constructed counting head.

Fig. 3 is a face view of the counting head 35 showing one of the drops in the released position.

Fig. 4 is a vertical section through the counting head taken on line IV—IV of Fig. 2.

Fig. 5 is a horizontal section of the same taken on line V—V of Fig. 3, and,

Fig. 6 is a detailed view of the shaft and pulley.

Similar reference characters refer to like 45 parts of the device throughout the several views, and the numeral 7 designates a ball-rolling track which terminates in an upwardly disposed and forwardly extending semi-circular end which carries the housing 50 of the counting head 8 in such a manner that the thrown ball 9 will enter as shown in Fig. 2 to strike the pivotally mounted pins 10 supported within the counting head adjacent the ball entrance.

55 It is known that this arrangement is old in the art, and it is understood that the

improvements set forth herein do not pertain specifically to the above-set-forth portion of the amusement device.

As is customary, the pins each are operatively connected to a counting drop 12 by a cable and latch mechanism 13. Through this mechanism, the striking of any one of the many pins 10 will cause the release of a counting drop 12 which, as shown in the drawing, is slidably mounted against the face of the counting head by grooved strips 14. When the counting drops are released to fall to the position shown in Fig. 3, a numeral or other suitable indicating mark 15 is revealed. When the counting drops 12 are in the set position, the numeral or the like is concealed therebehind.

Heretofore, the mechanism used to return the counting drops to the set position has been highly complicated, often hindered the falling of the counting drop 12 at the desired dropping time, and was expensive to make. Accordingly, the invention contemplates the use of simple 50 mechanism as fully illustrated herein and essentially including a shaft 15 extending across the counting head at a point spaced to the rear of the face thereof. This shaft 15 rigidly supports a plurality of arms 16 55 each of which extends forwardly through a slot 17 formed in the front wall of the counting head. As will be noticed from the drawing, each of the arms 16 terminates at a point near the bottom of the slot 17 to 60 engage beneath the bottom of the drop when it is in the lowered position. Thus, each arm 16 becomes a stop for the downward movement of the respective drop 12. After the desired number of drops have been released, it is possible to return them to the 65 set position through the shaft and arm structure simply by rotating the shaft through the use of any suitable means such as the pulley 18, rigidly secured to one end of the 70 shaft 15 outside of the counting head.

The manner in which this pulley is attached to the shaft may vary, but this method is deemed the most inexpensive. A plate 19, having a squared opening is rigidly 75 secured to the pulley through the use of screws or the like 20, and engages the squared end 21 of the shaft 15. To keep the assembly from slipping off, the machine 80 screw 22 may be screwthreaded into the end 110 of the shaft as shown in Fig. 6.

To rotate the shaft, a cable 23 is passed

part way around the pulley 18, and extends to a suitable lever 24, positioned near the player's location. A spring or other retrieving means 25 is affixed to the pulley 18 to yieldably maintain it in the ready position.

Another structural refinement found in the device made in accordance with this invention is shown in Figs. 2, 4 and 5. This refinement refers to the ball returning means which, in this invention includes a trough having an angled side 26 and an inclined bottom 27 which is lower at the ball return passage 28 than at its opposite end. Another side of the trough is shown at 29, and is disposed in a position to positively preclude the thrown ball 9 from returning through the opening through which it entered the counting head. This trough assembly is located beneath the pivotally mounted pins 10, and the sides thereof as well as the pin stops 30 and the ends of the pins, are covered with resilient material.

By combining these refinements of structure with the game device known in the art, the inventor has produced a finished product having very desirable qualities.

Having thus described the invention, what is claimed and desired to secure by Letters Patent is:

- 30 1. In a counting head for games of the character described, a plurality of slidably mounted drops mounted for movement over the face of said head, a slot formed through said face behind the path of travel of each drop respectively, a shaft rotatably mounted within said head having an arm extending through each of said slots respectively for operative engagement with the respective drop and means for rotating said shaft to cause the arms to travel through said slots to lift the drops to the set position.
- 40 2. In a counting head for games of the character described having a plurality of slidably mounted counting drops, means for returning said drops to the set position including a shaft, a plurality of arms integral with said shaft and positioned to engage beneath each of said drops respectively and means for rotating said shaft.
- 45 3. In a counting head for games of the character described having a plurality of

slidably mounted counting drops, a plurality of slots formed behind the path of travel of said drops and means for returning the same to the set position including a rotatable shaft 55 having a plurality of arms each extending exteriorly of the head through its respective slot, said arms adapted to form stops for the drops to limit their movement when they are released to slide from the set position. 60

4. In a counting head for games of the character described having a plurality of slidably mounted counting drops, a like number of slots formed through the face of said head behind the path of travel of each drop respectively, a rotatable shaft having a plurality of laterally extending arms each passing through a slot to engage the respective drop when it falls to the released position, manually operable means for rotating said shaft to lift said drops to the set position and means for retrieving and yieldably maintaining said shaft and arms in the ready position.

5. In a counting head for games of the character described having a plurality of pivotally supported drop releasing pins, means for guiding the pin actuating ball to the ball returning passage of said game including a cushioned ball stopping wall, an inclined floor in juxtaposition to said wall having its lowermost end adjacent said passage and a combined cushioned partition and guide wall cooperating with said first mentioned wall and floor to insure proper return of the ball and preclude its leaving said counting head through the ball entrance.

6. In a counting head for games of the character described, a plurality of ball actuating pins and means for catching and returning said ball to the player including a trough disposed beneath said pins having an inclined floor, a cushioned ball-stopping wall of comparatively great height disposed 95 at an angle to guide the ball into said trough and a combined guide and partition wall adapted to preclude the return of said ball through the entrance to said counting head.

In testimony whereof, I hereunto affix my signature this 18th day of January, 1927.

ARTHUR A. PAYNE.
